[57] **CLAIM**

The ornamental design for a pair of bicycle handlebar grips, as shown and described.

DESCRIPTION

FIG. 1 is a side elevational view of a pair of bicycle handlebar grips showing my new design, it being understood that the broken lines are for illustrative purposes only and form no part of the claimed design;

FIG. 2 is a left end elevational view of the left hand grip thereof;

FIG. 3 is a cross sectional view taken thereof along the 3—3 in FIG. 1; and,

FIG. 4 is a top plan of the right hand grip thereof, the bottom appearing the same as shown in FIG. 2. The side opposite to that shown in FIG. 1 is a mirror image of that shown in FIG. 1.

FIG. 2

FIG. 3

FIG. 4
